(57) CLAIM

The ornamental design for a dispensing lid, as shown and described.

DESCRIPTION

FIG. 1 is an elevated perspective view of the ornamental design for a dispensing lid showing our new design;

FIG. 2 is an elevated perspective view with the cap raised showing the deep well of the dispensing lid;

FIG. 3 is a top view thereof;

FIG. 4 is a side view, the other side being a mirror image thereof showing the oval cap of the dispensing lid;

FIG. 5 is a front view thereof showing the curved lip and the wide hinge of the dispensing lid and an interior section of the cap where molded instructions may be displayed;

FIG. 6 is a rear view thereof; and,

FIG. 7 is a bottom view thereof.
